US00D863357S

(12) **United States Design Patent** (10) Patent No.: **US D863,357 S**
(45) Date of Patent: **** Oct. 15, 2019**

(54) **COMMUNICATION DEVICE**

(71) Applicant: **OVERKIZ**, Metz-Tessy (FR)
(72) Inventor: **Didier Epain**, Poisy (FR)
(73) Assignee: **OVERKIZ**, Epagny Metz-Tessy (FR)
(**) Term: **15 Years**

(21) Appl. No.: **35/504,364**

(22) Filed: **Dec. 29, 2017**

(80) **Hague Agreement Data**

Int. Filing Date: **Dec. 29, 2017**

Int. Reg. No.: **DM/099384**

Int. Reg. Date: **Dec. 29, 2017**

Int. Reg. Pub. Date: **Feb. 2, 2018**

(30) **Foreign Application Priority Data**

Nov. 3, 2017 (EM) 004493336-0001

(51) **LOC (12) Cl.** **14-03**

(52) **U.S. Cl.**

USPC **D14/496**
